(57) **CLAIM**

The ornamental design for a medication container, as shown and described.

DESCRIPTION

FIG. 1 is a top perspective view of a medication container, showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dot-dash broken lines immediately adjacent to the claimed areas in the views represent the boundaries of the design and form no part thereof. Portions of the medication container shown in evenly-sized broken lines form no part of the claimed design.
